UNITED STATES PATENT OFFICE

JAMES A. WALKER, OF ROCKVILLE CENTER, NEW YORK

EXPANSION BAG

Application filed August 5, 1927, Serial No. 210,935. Renewed October 29, 1930.

My invention relates to bags or sacks and particularly to those used for containing and shipping commodities in divided form, from those which like potatoes are very coarse in 5 their division, to those which like cement in the powdered form are very finely divided. Great difficulty has heretofore been experienced in producing containers of this character which would be at once cheap to

10 make, and possessed of sufficient tensile strength to resist rupture and prevent loss of the contained materials when exposed to sudden strains or stress. An additional property which has been sought in many pro-

15 posed designs, is that of impermeability for finely divided materials. Paper properly treated fulfills the last condition, but has not the tensile strength in its ordinary form to resist sudden strains unless, as stated by

20 Mallalieu in U. S. Letters Patent 194,359, August 21, 1877, it is so strong and thick as to make the paper bags quite costly. Mallalieu proposed a paper lined textile bag, as did also Arkell in U. S. Letters Patents 565,587

25 August 11, 1896 and 686,877, November 19, 1901. Such construction however is not only more expensive than is justified by modern conditions but it also makes a non-homo-

30 geneous product, which cannot be employed uniformly for all purposes, with differences only in grade, as in the case of paper bags. Furthermore, while the desirability of water proofing such bags has been well known (see

35 U. S. Letters Patent to Bower 232,930, October 5, 1880), the combination of textile and paper fabrics is not adapted to successful water proofing, as the usual medium employed for uniting the two is some kind of

40 paste, which is hygroscopic, and the textile itself in most forms will absorb moisture, thus weakening the structure as well as defeating its object.

In the Arkell Patent 565,587, a vertically creased paper lining was used, but the patentee still found it necessary to employ the textile envelop, with all its disadvantages, in order to secure the necessary tensile strength to resist strains, the paper being 45 expandible.

In the Arkell Patent 686,877, the paper fabric is strengthened by making the constituent fibers run in lengthwise directions the same as the crinkles. The textile envelop is depended upon however for ultimate tensile strength, the purpose of expansion of the paper being to permit the latter to come into intimate contact with the textile envelop without being ruptured.

A later proposal of the same type as Arkell's is found in the U. S. Letters Patent to Jagenberg, 1,078,682, November 18, 1913, in which the outer fabric is woven of paper, with a crêpy lining inside. This however is open to the same objection of costliness in 55 production, and non-uniformity of product, because such bags cannot be used for an entire line of goods of varying character. Other paper lined fabric bags have been proposed and patented but none of them can be 60 used to attain the objects of my invention which may be stated as follows: production of a bag which shall be homogenous, that is, all of one material so that for all grades and sizes the same material will be used; that the 65 bag so produced shall be of cheap material such as paper that can be discarded after one use if desired; that the thickness of the paper may vary with the commodity involved; that the bag shall be so constructed that it will 70 resist the entrance of moisture; that no hygroscopic material shall enter into its construction; that the material shall be susceptible of complete water proofing without altering its character or the character of the 75 bag; that the bag shall resist rupture due to any sudden strain, from whatever direction, as for example by dropping it when filled with heavy finely divided material; and finally, that the design shall be simple enough 80 to permit quantity production on bag machines of ordinary commercial type, as such machines may be necessary.

I attain my objects, and avoid the objections previously stated, by the following 85 means: I make my bags entirely of soft, pliable paper, and at the present time I prefer to employ for this purpose what is known as kraft paper, in which there is a long soft fiber which gives considerable tensile 90 100

strength. By means of my construction I am enabled to use paper of relatively light weight, and since the design is the same throughout all sizes and grades, I can proportion the cost to the use so that the bag can be discarded; I can make my bag of a plurality of layers of paper with the grain or long fiber of successive layers crossing at right angles, commonly known as "crossing the grain", and seal the ends so that the entire structure is of itself moisture resisting; I secure the layers together by stitching or other means which involve no hygroscopic material; I use paper in such form that one or more of the layers may be impregnated with paraffin, or any material for water proofing purposes; I produce resistance to rupture in my bag by constructing alternate layers of soft pliable paper corrugated or crinkled, folded, pleated or creased in directions at right angles to each other; and finally, I follow commercial designs for the bag itself, and conform the multi-layer fabric to such design, so that quantity production may be attained in the ordinary way, without special features.

I am aware that in paper decorations and for other purposes it has been proposed to crinkle or corrugate the same sheet of paper in opposite directions but such material has never been used in a bag, nor would it be suitable therefor, as it has no resisting properties in any direction, and could not be employed to lift or carry. I believe that I am the first to employ separate corrugated or crinkled layers of paper put together in the manner and for the purpose stated; also corrugations or crinkles, folds, pleats or creases at right angles to each other, and I shall claim the same accordingly.

My invention is illustrated in the accompanying drawings, in which

Fig. 1 is a face view of a bag constructed of five layers of crinkle paper, each layer being cut away sufficiently to show the layer beneath it.

Fig. 2 is a section on an enlarged scale of the type of paper employed in the bag of Fig. 1.

Fig. 3 is a view similar to Fig. 1, constructed of five layers of corrugated kraft paper, with the corrugations in successive layers at right angles to each other.

Fig. 4 is a view on an enlarged scale of a fragment of the paper employed in the bag of Fig. 3.

Fig. 5 is a view similar to Fig. 1, showing a modification in which one bag or layer is crinkled, folded, pleated or creased, and the other or others are made of corrugated paper.

Fig. 6 is a fragmentary view on a larger scale of paper having groups of corrugations separated by plain portions without corrugations.

Referring to Fig. 1, 1 is the bag or sack composed of layers of paper 2, 3, 4, 5, the type

of paper being illustrated in Fig. 2, and commonly called "crinkled paper". In Fig. 1, the crinkles in No. 1 or the outer layer of the bag run vertically. In layer 2 they run horizontally; in layer 3 they run vertically; in layer 4 they run horizontally, and in layer 5 they run vertically. In case only two layers, as 1 and 2 are employed, No. 1 would have its crinkles vertical and 2 would have its crinkles horizontal, or vice versa. The long soft and pliable fibers run in the same direction as the crinkles, for tensile strength. The same object, of imparting tensile strength to the walls of the bag longitudinally and transversely may be measurably attained, as I have found by experimentation, with sufficient tensile strength for my general purpose, by corrugating the paper in other directions than parallel to the long fibers. This occurs when paper is corrugated as it comes off the roll, since the long fibers are necessarily produced lengthwise of the web in manufacture. It is obviously more economical to corrugate the paper as it comes from the roll than to cut sheets and corrugate them afterward, and I wish therefore to include this construction as a modification of that first stated, and as within the scope of my invention.

A still further modification, which lies rather in the method of producing the bags than in the structure of the paper, is the following: Produce the bag from plain paper, preferably in cylinder form, which is the product of the ordinary bag machine. Then with the bag ready to be closed at the ends, run it through the corrugating machine and produce corrugations either longitudinal or transverse, as may be desired. If for example it be found economical in manufacture to take the web as it comes from the rolls and turn it, glue it, and cut it off, then the long fibers would run around the body of the tube thus produced. If now the tube be flattened and run through the corrugating machine or crinkling machine, obviously the direction of feed through the rolls determines the direction of the corrugations with respect to the long fibers. If the corrugations are produced lengthwise of the tube they will be transverse to the long fibers and if transverse to the length of the tube then they will be parallel with the long fibers. I consider this method of producing the bags by first forming the same and then corrugating them, to be a part of my invention and shall claim the same accordingly.

As a further modification of the method of producing the bags, especially with respect to the use of water proof material, before corrugating and before forming the bag, I preferably treat the paper with water proofing substance such as bitumen or asphalt compound or the like. A convenient way of doing this is by using two separate layers

of paper with the water proof compound between them. As this and other methods of water proofing paper are known, I lay no claim to the same as such, but I do claim as 5 my own the step of first water proofing the paper in any suitable manner, as for example by the means mentioned, and then corrugating the paper in its final form, either in the sheet or roll, or in the tube form produced by the bag machine.

10 Referring to Figs. 3 and 4, 11 is the body of a sack similar to 1 in Fig. 1, but constructed of corrugated pliable kraft paper, which may be made heavy enough to have any desired tensile strength and in which the long 15 fibers of the paper run in the same direction as the corrugations. The layers 7, 8, 9, 10, 11 have their corrugations alternately at right angles to each other, and the result is 20 the same, except for a little greater stiffness, as with the bag of Fig. 1.

In using these bags for commodities like flour, cement or any other finely divided material, it is in accord with good practice to 25 seal the bags at both ends and fill them through valves, which I have indicated at 12 in Figs. 1 and 3. These valves are usually formed by folding the corners in before 30 stitching, so that the stitching holds them in place. When filling the bag, the filling nozzle is introduced through the valve and when 35 the bag is full and the filler removed, the sides of the valve collapse under the weight of the material in the bag, as shown for example in the Bates Patents 623,198, April 18, 1899, and 683,894, October 8, 1901, and Rogers 829,431, August 28, 1906.

40 The lines of stitching which close the ends of the bag are indicated at 6 in Figs. 1 and 3 and it is to be understood that I may vary this method of fastening or substitute other methods for it without departing from the invention, the gist of which lies in the use of alternate layers with right angle corrugations running parallel with long fibers or across the same, and the securing together of the layers without any hygroscopic material, whereby the entire bag and every part thereof will work as a unit both in lifting 50 and resisting strains, and will offer a resistance to the latter equal to 100% of the tensile strength of all the material in the bag.

55 Referring to Fig. 5, I have therein shown a modification employing layers of mixed character, as follows: 14 represents the outside bag made of crinkled pliable paper, with the crinkles horizontal; 15 represents the first inner bag of corrugated pliable paper with the corrugations vertical; 16 is the second inner bag made of corrugated pliable paper with the corrugations horizontal or at right angles to the corrugations of the first inner bag; and 17 is a third inner bag made of corrugated pliable paper with corruga-

tions vertical, or at right angles to the corrugations in the second bag.

A feature of the corrugated paper which may be employed in the bag of Fig. 5, or for that matter, in any form of the bag, is shown 70 separately in Fig. 6 where the paper of a layer is indicated as having its corrugations in groups, separated by strips of plain paper without corrugations. The relative dimensions of the corrugated and uncorrugated 75 portions of the paper as well as the number and size of the corrugations, will determine the degree of its expansibility. The use of such paper is indicated in Fig. 5, but it is of course understood that I am not limited 80 thereto.

In the following claims I shall specify the paper I employ, including the kraft paper as "pliable", or "soft and pliable", or as having soft or pliable fibers, by which I mean 85 that the paper employed is without stiffness, but may be bent, twisted, folded, etc., without straining the fiber and without breaking it. This is distinguished from "flexible", in the same manner that a soft fabric is distinguished from a cardboard.

What I claim is:

1. A bag consisting of a plurality of pliable layers of paper disconnected from each other and free to move one upon another 95 except along lines of closure of the bag, each layer being gathered or corrugated in one direction, and the alternate layers having their gatherings or corrugations at right angles to each other.

2. A bag consisting of two pliable layers, each layer being provided with a series of ridges and intermediate grooves arranged transversely with respect to the ridges and grooves of the other layer, each layer being 105 free to contract and expand its ridges and grooves at right angles with respect to the other, except at the lines of closure of the bag.

3. A bag composed of successive pliable 110 layers of homogeneous material, one layer being expansive in one direction and resisting expansion in the other direction, and the second layer resisting expansion in the first direction but being expansible in the other, 115 said layers being independent of and freely movable on each other except at the lines of closure of the bag.

4. A bag made of paper fabric in a plurality of pliable layers, each layer having 120 the length of its constituent fibers running generally in one direction and having crinkles or corrugations, folds, pleats or creases running in the same general directions with respect to said fibers, and the alternate layers having the direction of their fibers and their crinkles or corrugations at right angles 125 to each other, whereby the capacity of the fabric to maintain itself without breaking against strains in either direction is greatly

augmented, said layers being independent of and freely movable on each other except at the lines of closure of the bag.

5. A paper bag formed of a compound paper fabric built up in pliable layers, each layer being crinkled or corrugated and alternate layers having their crinkles or corrugations at right angles to each other, and water proof means closing the ends of the bag, said layers being independent of and freely movable on each other except at the lines of closure of the bag.

6. The method of producing a strain resisting fabric bag which consists in corrugating, crinkling, folding, pleating or creasing pliable paper sheets, forming tubes of said sheets adapted to fit one within the other, with the corrugations of alternate tubes running in opposite directions to each other, and closing the ends of said tubes, said layers being independent of and freely movable on each other except at the lines of closure of the bag.

7. A paper bag formed of a compound paper fabric built up in pliable layers, each layer being crinkled or corrugated and alternate layers having their crinkles or corrugations at right angles to each other, water-proof means closing the ends of the bag, and one of the layers treated with suitable water proof material, said layers being independent of and freely movable on each other except at the lines of closure of the bag.

In testimony whereof I hereunto affix my
35 signature.

JAMES A. WALKER.
